Primary Examiner — Barbara Fox*Assistant Examiner* — Messina L Smith(74) *Attorney, Agent, or Firm* — Matthew G. McKinney, Esq.; Allen, Dyer et al.(57) **CLAIM**

The ornamental design for a hair clip, as shown and described.

DESCRIPTION

FIG. 1 is a top perspective view of a hair clip showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines shown in the drawings depict stitching that forms no part of the claimed design.

1 Claim, 5 Drawing Sheets(56)
